CHIPPER KNIFE GRINDER

George M. Standal, Chemainus, British Columbia,
Canada

Filed May 15, 1959, Ser. No. 813,393

4 Claims. (Cl. 51—55)

My invention relates to a chipper knife grinder. It is particularly directed to a grinder so arranged as to grind a chipper knife which requires one ground face to be in a plane and another ground face to be curved. It is the purpose of my invention to provide a grinder of this nature wherein both faces are ground at controlled rates, pre-set by the operator, and wherein the grinding wheels are advanced toward the work from the same base control to assure maintenance of the proper ratio of grinding between the curved and plane surfaces.

Other objects and advantages of my invention will appear from the following description and the accompanying drawings wherein a preferred form of the invention is shown.

In the drawings:

Figure 1 is a front face view of a chipper knife grinder embodying my invention;

Figure 2 is a fragmentary bottom plan view of a portion of the grinder;

Figure 3 is a plan view of the grinder;

Figure 4 is a side view of the grinder looking at Figure 1 from the left side;

Figure 5 is a rear face view with parts broken away of the grinder;

Figure 6 is an enlarged fragmentary bottom view, looking at Figure 1 from the line 6—6;

Figure 7 is an enlarged sectional view taken on the line 7—7 of Figure 3;

Figure 8 is a sectional view taken on the line 8—8 of Figure 7;

Figure 9 is a bottom plan view of a chipper knife that is sharpened by the grinder; and

Figure 10 is a fragmentary sectional view taken on the line 10—10 of Figure 6.

My invention is embodied in a grinder wherein the knives 40 are mounted on a rotatable head 2 which is supported by its drive shaft 3. The shaft 3 is mounted by two bearings 4 and 5 on standards 6 and 7 that extend up from a hollow base 8. A main motor 9 is mounted on the base 8 and is connected by a shaft 10 to a speed reduction gear unit 11, also mounted on the base 8. The unit 11 has a shaft 12 provided with two sprocket wheels 13 and 14 which drive chains 15 and 16 respectively. The drive shaft 3 has a sprocket wheel 17 thereon which is driven by the chain 15. The chain 16 extends through the top 8a of the base 8 and drives a worm shaft 18 that is suspended in bearings 19 and 20 from the top 8a.

The worm shaft 18 has a worm 21 thereon which drives a worm gear 22 that is fixed on an upright shaft 23. The shaft 23 is rotatably supported in a pedestal 24 that has a base plate 25 bolted to the base 8. Beneath the gear 22 the shaft 23 has a crank arm 26 fixed thereon. The crank arm 26 has a rod 27 pivoted thereon that connects to a crank arm 28 fixed on a shaft 29 that is rotatably supported in a pedestal 30. The pedestal 30 has a base plate 31 that is adjustably mounted on the base 8 by bolts 32 that extend through elongated slots

2

33 in the base 8 and elongated slots 34 in the plate 31. The shaft 29 supports a grinding unit 35 which will be described more fully hereinafter.

The shaft 23 also has a crank arm 36 fixed to the upper end thereof above the pedestal 24. A rod 37 is pivoted on the crank arm 36 and connects to a grinding unit 38 which will be described more fully hereinafter.

The knife 40 which is to be ground by this grinder is illustrated in Figure 9. It comprises a base portion 41 and an upturned nose portion 42. The two portions 41 and 42 are curved where they join. The faces 41a and 42a have to be ground in such a fashion as to present a cutting edge which has the peculiar configuration shown. The nose portion 43 of the edge is forwardly of the junction 44 between it and the edge portion 45 on the base portion 41 of the knife. The nose portion 42 may be on either the right hand or the left hand side of the portion 41.

20 The head 2 carries a plurality of mounting blocks 46 for mounting the knives 40. As shown, there are seven such blocks bolted to the periphery of the head 2 which is disk-like with strengthening ribs 2a and a hub 2b.

Each block 46 has provision for mounting the knives 40, one a right hand knife and the other a left hand knife. The block 46 has a two channelled projection 47 thereon which projects in a direction parallel to the shaft 3 of the head 2. The projection has its channels 49 and 50 open outward so as to receive the knives 40 therein. One channel is for right hand knives 40, the other is for left hand knives. The channels 49 and 50 are closed at the back as indicated at 51 to control the amount a knife projects beyond the face of the channel. In each channel there is a clamp bar 53 which is carried by the front wall 54 of the channel on a cap screw that can move a limited amount through the wall 54 and is threaded into the bar 53. The walls 54 are also threaded to receive two set screws 55 and 56 which press the clamp bar 53 against a knife 40 seated in the channel. The projection 47 and the clamp bars 53 are bevelled across the front to parallelism with the plane of rotation of the head 2.

It will be appreciated that in view of the peculiar configuration of the knife 40 the channels 49 and 50 do not extend radially with respect to the head 2. They are set at such angles to a plane perpendicular to the axis of rotation of the head 2 and to a radius from the head hub 2b through them that the proper slope of the cutting edge 45 on the knife 40 will result from passing

50 a grinding wheel face across the knife face 41a in a plane perpendicular to the axis of rotation of the head 2. The channels are also set at such an angle that the nose face 42a can be rounded by grinding. As shown, the nose faces 42a of both right hand and left hand knives 40 are 55 directed so they curve toward the back of the block 46 from the plane of the face 41a which is parallel to the back face 2c of the head 2.

The grinding unit 35 is the unit which grinds the nose faces 42a. It comprises a supporting arm 58 fixed on the 60 shaft 29, a mounting stem 59 on the arm 58, and a platform 60 on the stem 59. On the platform 60 there is a slidably mounted motor 61 which carries a grinding wheel 62. It will be appreciated that, since the shaft 29 can be shifted, by reason of the adjustable mounting 65 of the pedestal 30 provided by the slots 33 and 34 and the bolts 32, the position of the axis of the shaft 29 with respect to the path of the nose of a knife 40 clamped to the head 2 can be pre-set correctly. After that the end-wise movement of the motor and grinding wheel toward 70 the work is accomplished by sliding the motor 61 on the platform 60.

The means for sliding the motor 61 on the platform

60 comprises a shaft 63 which is journalled in the platform 60 at its ends and which has a threaded portion 64 that is threaded in a depending boss 65 on the motor base 61a. A handwheel 66 is fixed to the shaft 63 and has peripheral gear teeth 67 which mesh with a pinion 68. The pinion 68 is fixed on a shaft 69 that is journalled in bearings 70 depending from the platform 60. The shaft 69 has a ratchet wheel 71 at its end remote from the pinion 68. Turning the handwheel 66 can be done by the handle 72 or by turning the ratchet wheel 71.

To accomplish automatic turning of the ratchet wheel 71, I provide a pawl 73 pivoted on a post 74. The post 74 is mounted on the base plate 31 and holds the pawl in the path of the ratchet wheel 71. An adjustable stop 75 is threaded into the post 74 and leaf spring 76 fixed on the post 74 yieldingly holds the pawl against the stop 75, but allows the pawl to slip over the teeth of the ratchet wheel 71 when the wheel is moving away from the post 74. With this construction when the shaft 29 is oscillated by the crank arm 28 and the rod 27, the grinder 35 is moved in an arc to cause the wheel 62 to traverse each knife nose that is moved past it by the head 2. At the finish of each stroke of the grinder 35 toward the post 74, the pawl 73 engages the ratchet wheel 71 and turns it a fraction of a turn. This causes the pinion 68 to turn the handwheel 66 which will advance the motor 61 and grinding wheel 62 toward the path of the noses of the knives 40. The grinding wheel 62 can always be brought to the work or away from it by turning the handwheel 66 whenever the pawl 73 is out of engagement with the ratchet wheel 71.

The grinding unit 38 is supported to swing toward and away from the axis of the head 2 on an upright arm 78 which is fixed on a shaft 80 that is journalled in bearings 82 on the base 8. At the top of the arm 78 a platform 83 is fixed. On this platform a motor 84 is slidably mounted in the same manner as the motor 61 on the platform 60. The motor 84 carries a grinding wheel 85. A handwheel 86 has its shaft 87 connected to the motor 84 in the same manner as the shaft 63 is connected to the motor 61. A pinion 88 is fixed on a shaft 89 that is suspended by bearings 90 and 91 from the platform 83. The pinion 88 meshes with the teeth 86a on the handwheel 86. The shaft 89 has a ratchet wheel 92 fixed thereon. A post 93 fixed on the base 8 carries a pawl 94 that is adapted to engage the wheel 92 as the platform 83 moves toward the post 93. The pawl 94 engages an adjustable stop 95 on the post 93 and is yieldingly held against the stop by a leaf spring 96 fixed to the post 93. In order to swing the platform to and fro the rod 37 is pivotally connected to the platform 83.

It is believed that the construction of my chipper knife grinder will be clear from the foregoing description. To grind a set of seven right hand knives 40 and seven left hand knives 40 alike, the several knives are clamped in the channels 49 and 50. The grinding wheels 62

and 85 are moved by hand, adjusting the handwheels 66 and 86 until the wheels contact the work. Then the motors 9, 61 and 84 are started and the grinding continues until the knives are sufficiently sharpened. The head 2 rotates the several knives past the grinding wheels 62 and 85 at a rapid rate (for example, 50 r.p.m.), while the wheels are rotated at high speed by their motors 61 and 84 respectively. The rods 27 and 37 are actuated by the shaft 23 to reciprocate the units 35 and 38 to and fro slowly. The pawls 73 and 94 engage their respective ratchet wheels 71 and 92 just before the termination of the reciprocating movement in one direction to advance the grinding wheels for the next stroke across the work and back.

Having described my invention, I claim:

1. A grinder for chipper knives comprising in combination, a base, a knife carrying head, a shaft supported for rotation on said base and carrying said head, a plurality of knife carrying blocks on said head equally spaced from the shaft axis, each block including means to clamp thereon a knife having a planar portion and an upturned nose thereon with the cutting edges of the planar portions of the knives in a plane perpendicular to the shaft and the noses of the knives facing outwardly and receding from said plane, a first grinding unit mounted on said base for reciprocal movement in a direction perpendicular to said shaft, and having a grinding wheel facing toward said head, means to reciprocate said grinding unit, a second grinding unit mounted on said base for reciprocating movement about an axis substantially tangent to the path of rotation of the blocks and means to reciprocate said second grinding unit.

2. The invention defined in claim 1, together with means operable by the first and the second grinding units to advance them toward the knives at the end of each reciprocation thereof.

3. The invention defined in claim 1 wherein the said clamping means comprises slots in said blocks open toward the first grinding unit and open radially outward, clamp bars mounted in said slots and means to force each clamp bar against a knife placed in the slot in which the bar is mounted.

4. The invention defined in claim 1 wherein the means to reciprocate said grinding units comprise a common drive shaft, a horizontal shaft pivoted on the base, arm means pivoted on said horizontal shaft and carrying the first grinding unit, a crank arm on the common drive shaft linked to said arm means, a vertical shaft pivoted on the base and carrying the second grinding unit, and crank arms and a link connecting the vertical shaft to the common shaft.
